UNITED STATES PATENT OFFICE.

HARRY B. SNYDER, OF CHICAGO, ILLINOIS.

DESIGN FOR A CANE-HANDLE.

SPECIFICATION forming part of Design No. 22,340, dated April 11, 1893.

Application filed February 18, 1893. Serial No. 462,918. Term of patent 3½ years.

To all whom it may concern:

Be it known that I, HARRY B. SNYDER, a citizen of the United States, residing at Chicago, in the county of Cook and State of Illinois, have invented and produced a new and original Design for Cane, Umbrella, and Parasol Handles, of which the following is a specification, reference being had to the accompanying drawing, which is a perspective view of my new design.

My invention pertains to cane, umbrella and parasol handles, such as may be preserved as mementos of the Columbian Exposition or World's Fair at Chicago.

My present invention relates to what are known as L-shaped or hooked cane, umbrella or parasol handles.

In the drawing the staff is shown broken away and upon the upper end is mounted a globe upon the surface of which are depicted the different divisions of the land comprised on the earth's surface. The bottom portion of the globe is provided with a thimble by which the handle is secured to the staff. Secured upon the upper portion of the globe and extending at right angles thereto is a standing figure of Christopher Columbus as represented in the painting "The Landing of Columbus." In this figure Columbus is represented as having a short, full beard, long flowing hair which extends to the shoulders, and the neck is bare. The figure is clothed on a short coat, the sleeves of which are fluted or puffed, and the lower limbs are clothed in a tight fitting garment such as worn during his time. In his right hand is grasped a sword, the point of which touches the ground between his feet, and his left hand rests upon his right.

Having thus fully described my invention, what I claim as new, and desire to secure by Letters Patent, is—

The design for a cane, umbrella and parasol handle herein shown and described.

In testimony whereof I hereunto affix my signature in the presence of two witnesses.

HARRY B. SNYDER.
